DISPENSING BOTTLE TOP

Bruno J. Christeck and Leonard Z. Plebanek,
Chicago, Ill.

Application July 9, 1949, Serial No. 103,832

13-Claims. (Cl. 222—38)

1

This invention relates to a liquid measuring device and it is an object of this invention to produce a self-measuring top for repeatedly dispensing predetermined quantities of liquid content material, one after another at short time intervals, while the bottle or other vessel containing the liquid content material is held in pouring position.

Another object is to produce the self-measuring repeating top of the type described, which is provided with means for preventing loss or withdrawal of liquid content material from the bottle or vessel, other than when the bottle is held in pouring position.

A further object is to provide, in combination with a self-measuring repeating top of the type described, a metering device which automatically records the number of measured units which have been dispensed from the bottle top.

These and other objects and advantages of this invention will hereinafter appear and for purposes of illustration but not of limitation, an embodiment of the invention is shown in the accompanying drawings in which:

Figure 1 is a sectional elevational view through a dispensing bottle top embodying features of this invention;

Figure 2 is an elevational view partially in section, but taken at right angles of the bottle top shown in Figure 1;

Figure 3 is an enlarged perspective view of the actuator which forms part of the metering device;

Figure 4 is an enlarged perspective view of the part for adjusting the metering device to a desired starting position;

Figure 5 is an elevational view of the numbered ratchet wheel that is operated by the actuator and adjusted by the part shown in Figure 4;

Figure 6 is an enlarged sectional view taken along the line 6—6 of Figure 7, and

Figure 7 is an enlargement of the valve forming part of the air vent shown in Figure 1.

As shown in the drawing, the dispensing top embodying features of this invention has a hollow measuring chamber 50 formed by a pair of interfitting shells 34 and 35. The shells are joined along their interfitting edges, such as at 36, to provide an airtight sealing relation all around.

The assembled top has a tubular projection 51 fitted with a centrally apertured cap 38 which assists in holding the shells 34 and 35 together. The projection 51 has a passageway extending

2

therethrough which receives a dispensing conduit 16 having an end portion which extends outwardly from the projection as a pouring spout 10 and a portion which extends into the measuring chamber for a distance which will hereinafter be described. The dispensing conduit 16 is arranged to be disposed at a vertical angle with the spout down when the bottle or vessel is raised to pouring position and to be downwardly inclined with the spout uppermost when the bottle is returned to upright position. In this position any liquid that might be disposed within the conduit will drain back into the bottle.

Another projection 52 extends downwardly from the lower portion of the assembly top and it is provided with a pair of adjoining passageways, one of which is adapted to pass a short supply pipe 13 through which liquid content material drains from the bottle to the measuring chamber when the bottle is raised to pouring position. The other passageway is adapted to pass an air pipe 17 which has its outlet located in the lower portion of the bottle and its inlet 25 in communication with the base of the measuring cap 15 of the usual siphon.

The pipes 13 and 17 also extend through a cork 39 which is adapted to fit the neck of a bottle indicated by the Figure 8. A cap member 37 is provided about the projection 52 to assist in holding the shells together and with the packing 40 it establishes a sealing relation with the cork 39 to prevent the admission of air which would otherwise interfere with the operation of the measuring device.

The siphon consists of the cylindrical cup member 15, which is open at the upper end and closed at the lower end by wall 53. The cup member is disposed at an angle corresponding to that of the dispensing conduit 16. The conduit 16 extends through the upper open end of the cup to a position adjacent the lower end thereof, and the inlet 14 of the air pipe 17 is also located in this same region, but the end 45 of the air pipe is tapered to bring its lower edge flush with the lower wall and the rearward wall of the cup so that any liquid in the cup will drain into the air pipe 17 when the bottle is in upright position.

The measuring chamber 50 in the cap is vented to the atmosphere through aperture 9 located in the shell wall opposite the projection 51. To prevent inadvertent loss or escape of liquid from the measuring chamber whether or not the bottle is shaken, a valve is provided for passage

55 which communicates the measuring chamber 50 with a venting chamber 54 into which the vent 9 leads. The valve member shown is in the form of a ball 31 housed for slight movement within an enclosure defined by the front wall of the chamber 54 and vertically spaced horizontally disposed upper and lower walls 56 and 57. The upper wall has a depending end flange 58 and the lower wall has a rim 58a which provides a socket for the ball when the bottle is in the upright position. The ball prevents the use of the vent hole as a means for removing the liquid, even when the container is in an inverted pouring position. While seated in the socket the ball 31 closes the vent 55 thereby to prevent loss of content material. Responsive to gravitational force, the ball moves away from the vent opening when the bottle is raised to pouring position. It will be understood that other valve means may be provided in the passage to give a corresponding effect.

To prevent the escape of content material from the dispensing conduit 16, the conduit is provided with a ball 28 arranged within the conduit between a cross rod 30 and a tapered sleeve 29 in the conduit. The cross rod 30 prevents loss of the ball when the bottle is raised to pouring position and the ball seats in the sleeve 29 when the bottle is other than in pouring position, thereby to close the opening through the conduit 16 and prevent the escape or loss of content material.

A baffle 70 is provided in the lower portion of the measuring chamber. The baffle extends from the forward wall of the cap and beyond the supply and air pipes 13 and 17 and it is downwardly inclined to drain content material in the measuring chamber toward the pipes when the bottle is in upright position.

The measuring device operates on a siphon principle. For pouring, the bottle is tilted to a position whereby the spout 10 is down and the dispensing conduit 16 and the cup 15 are substantially vertical. When in this position, air passes through the conduit 16, through the cup 15, into air pipe 17, to replace liquid content material which drains through the supply pipe 13 into the measuring chamber 50.

Filling of the measuring chamber continues in this manner until the level of the liquid rises to the inlet end of the conduit 16, whereupon siphoning commences. At this point, air is unable to rise through the conduit 16 or enter the cup 15 from the vent 9. Thus, air is cut off from the air pipe 17 and fluid is no longer able to drain from the bottle into the measuring chamber. The vent 9, permits atmospheric pressure to be maintained within the measuring chamber for siphoning purposes.

Siphoning of the liquid from the measuring chamber continues until the fluid level has reached the lower open edge of the cup member 15, whereupon air passage to the air pipe 17 is re-established and fluid no longer passes through the conduit. This frees the conduit for air supply and the described cycle is repeated.

This consecutive filling and siphoning of measured quantities of content material continues so long as the bottle is held in pouring position. It will be evident that the amount of liquid entering the measuring chamber is constant and predetermined by the length of the cup 15 and the distance which the conduit 16 extends into the cup. The time lag occasioned for refilling the measuring chamber before siphoning can again take place is usually sufficient for changing re-

ceiving vessels, if desired. In the event that the time lag is insufficient, it may be slowed by various means designed to restrict the flow of content material into the measuring chamber, such as by restricting the rate of air flow into the bottle or by restricting the rate at which content material may drain from the bottle into the measuring chamber.

To record the number of cycles through which the dispenser has gone, the measuring chamber is provided with an actuator arranged therein comprising a float 18 carried on one end of a pair of V-shaped lever arms 59 and 60 having out-turned ends 61 and 62 respectively pivotally mounted in suitable bearings formed in the shell walls. A spring dog 21 is carried by one of the arms 60 intermediate its ends. The spring dog normally rests on a pin 22 but when the float rises with the level of liquid in the measuring chamber, the operative end 63 of the spring dog engages one of the numbered rack teeth 23 arranged in measured spaced relation about the periphery of a ratchet wheel 64 which is mounted on the some float arm for free turning movement.

Inadvertent turning movement of the ratchet wheel is prevented by a lock spring 24 which is secured at one end to the underside of wall 56. The free end of the lock spring engages the rack teeth to provide a steady action. The ratchet wheel 64 is formed of one tooth missing, as at 26 before the zero position, to prevent the spring dog 21 from actuating the ratchet wheel beyond the highest numbered tooth. Numbers 32 may be applied to indicate each tooth or to indicate a certain number of teeth, as shown in Figure 5. Numbering may be accomplished with substances visible in ordinary daylight or they may be formed of fluorescent materials visible only under black light.

The ratchet wheel is adjusted to indicate a desired number by an adjusting bracket shown in Figure 4 which is disposed within the area defined between the baffle 70 and the lower wall of the cup. The adjuster consists of another spring dog 25 on the outer end of a body portion 65 which is pivoted from the slotted portion 66 about the air pipe 17. The other end is provided with an upturned spring member 67 which engages the under side of the baffle 70 in a manner constantly to urge the adjuster to rock in a counterclockwise direction. To adjust the ratchet wheel, it is necessary to work through the supply tubing 13 with a rod, indicated by the numeral 11. The rod is actuated to the end portion 25 causing the adjuster to rock in a clockwise direction and bring the upturned end 67 into operative engagement with an adjacent tooth. The ratchet wheel is turned one step responsive to the spring action upon withdrawal of the rod 11.

This arrangement permits accurately dispensing measured amounts of content material in repeated fashion with means embodied within the device accurately to record the number of units which have been dispensed. Such recording cannot be disturbed other than by removal of the measuring cap which would be indicated by breaking the seal formed thereon, indicated by the numeral 12. To prevent actuation of the ratchet wheel by any other manner than by raising the bottle to pouring position a pivoted stop 27 is provided having a free end portion 68 which extends into the path of the float 18 while the bottle is in upright position. The stop is in the form of a bell shape lever suspended intermediate its ends over the pin 69 extending from the shell

wall. The depending portion 10 of the bell lever is weighted to rock the stop out of position, as shown by the broken lines, when the bottle is raised to pouring position. This permits the float 18 to rise to the position shown by the broken lines as the level of the liquid rises in the measuring chamber. The actuator therefore can only operate to turn the ratchet wheel responsive to the rise in liquid level when the bottle is raised to pouring position.

From this description it will be apparent that we have provided a new and improved dispenser top for repeatedly dispensing measured quantities of content material while the bottle is held in pouring position. Our device embodies features which prevent loss of content material from the cap through any intention by the operator other than for dispensing measured quantities of liquid which are automatically calculated and recorded by reaction of elements embodied therein.

It will be understood that numerous changes may be made in the details of construction, arrangement and operation without departing from the spirit of the invention, especially as defined in the following claims.

What is claimed is:

1. In a measuring device of the type described operating on a siphon principle for repeatedly measuring predetermined increments of liquid content material from a vessel into a measuring chamber provided with an air inlet to maintain atmospheric conditions within said chamber and dispensing a measured quantity of the content material from the measuring chamber through a dispensing conduit while the device is in dispensing position, an indicator from which the number of units dispensed may be read, means responsive to the filling of the measuring chamber with the predetermined increment of liquid for operating the indicator to record such filling, a ratchet operative on the indicator and a pawl biased into engagement with the ratchet to prevent inadvertent adjustment of the indicator to make a different showing.

2. In a measuring device of the type described operating on a siphon principle for repeatedly measuring predetermined increments of liquid content material from a vessel into a measuring chamber provided with an air inlet to maintain atmospheric conditions within said chamber and dispensing a measured quantity of the content material from the measuring chamber through a dispensing conduit while the device is in dispensing position, an indicator from which the number of units dispensed may be read, means responsive to the filling of the measuring chamber with the predetermined increment of liquid for operating the indicator to record such filling, means resiliently engaging the indicator to prevent inadvertent adjustment thereof to make a different showing, and spring tensioned lever means having an end portion which operatively engages the indicator and another end portion adapted to be engaged from the under side of the device by an external force when the device is free of the vessel to effect adjustment of the indicator to a desired showing.

3. In combination with a measuring device of the type described which operates on a siphon principle for repeatedly measuring out predetermined increments of liquid content material from a vessel into a measuring chamber and automatically dispensing a measured quantity of the content material from the measured chamber when said chamber becomes filled with the predeter-

mined quantity, a registration device arranged within the measuring chamber for recording the number of units which has been dispensed including a numbered ratchet wheel mounted within the chamber for free turning movement, a float responsive to the level of the content material within the measuring chamber, and a dog operative with the float to engage the ratchet wheel, and advance said wheel one increment as the float rises to the level corresponding to a desired increment of content material within the measuring chamber.

4. In combination with a measuring device of the type described which operates on a siphon principle for repeatedly measuring out predetermined increments of liquid content material from a vessel into a measuring chamber and automatically dispensing a measured quantity of the content material from the measured chamber when said chamber becomes filled with the predetermined quantity, a registration device arranged within the measuring chamber for recording the number of units which has been dispensed including a numbered ratchet wheel mounted within the chamber for free turning movement, a float responsive to the level of the content material within the measuring chamber, a dog operative with the float to engage the ratchet wheel, and advance said wheel one increment as the float rises to the level corresponding to a desired increment of content material within the measuring chamber, and a spring lever fixed at one end to a wall of the device while the other end tensionally engages the ratchet wheel to militate against movement other than that responsive to the float while the device is in the mounted relation on the vessel.

5. In combination with a measuring device of the type described which operates on a siphon principle for repeatedly measuring out predetermined increments of liquid content material from a vessel into a measuring chamber and automatically dispensing a measured quantity of the content material from the measured chamber when said chamber becomes filled with the predetermined quantity, a registration device arranged within the measuring chamber for recording the number of units which has been dispensed including a numbered ratchet wheel mounted within the chamber for free turning movement, a float responsive to the level of the content material within the measuring chamber, a dog operative with the float to engage the ratchet wheel, and advance said wheel one increment as the float rises to the level corresponding to a desired increment of content material within the measuring chamber, and a dog engageable with the rack teeth of the indicator, said dog having a spring pressed portion which is accessible only when the device is free of the vessel to operate the dog for engaging successive teeth whereby the indicator may be adjusted to any desired position.

6. In combination with a measuring device of the type described which operates on a siphon principle for repeatedly measuring out predetermined increments of liquid content material from a vessel into a measuring chamber and automatically dispensing a measured quantity of the content material from the measured chamber when said chamber becomes filled with the predetermined quantity, a registration device arranged within the measuring chamber for recording the number of units which has been dispensed including a numbered ratchet wheel mounted within the chamber for free turning movement, a

float responsive to the level of the content material within the measuring chamber, a dog operative with the float to engage the ratchet wheel, and advance said wheel one increment as the float rises to the level corresponding to a desired increment of content material within the measuring chamber, a crank lever pivoted intermediate its ends with the depending arm weighted to urge the arm toward vertical position responsive to gravitational forces, the other arm extending angularly therefrom into the path of the float when the device is in other than dispensing position and to be rocked from the path of the float when the device is in dispensing position.

7. In a measuring device of the type described operating on a siphon principle for repeatedly measuring predetermined increments of liquid content material from a vessel into a measuring chamber provided with an air inlet to maintain atmospheric conditions within said chamber and dispensing a measured quantity of the content material from the measuring chamber through a dispensing conduit while the device is in dispensing position, an indicator from which the number of units dispensed may be read, means responsive to the filling of the measuring chamber with the predetermined increment of liquid for operating the indicator to record such filling, means resiliently engaging the indicator to prevent inadvertent adjustment thereof to make a different showing, means operative from an external source when the device is free of the vessel to adjust the indicator to a desired showing, valve means in the conduit substantially to close the passage therethrough while the device is in other than in dispensing position.

8. In a measuring device of the type described operating on a siphon principle for repeatedly measuring predetermined increments of liquid content material from a vessel into a measuring chamber provided with an air inlet to maintain atmospheric conditions within said chamber and dispensing a measured quantity of the content material from the measuring chamber through a dispensing conduit while the device is in dispensing position, an indicator from which the number of units dispensed may be read, means responsive to the filling of the measuring chamber for operating the indicator comprising a float responsive to the level of content material within the measuring chamber, an operative connection between the float and the indicator for effecting the desired registration when the float has risen to the desired level, means resiliently engaging the indicator to prevent inadvertent adjustment thereof to make a different showing, and means operative from an external source when the device is free of the vessel to adjust the indicator to a desired showing.

9. In a measuring device of the type described operating on a siphon principle for repeatedly measuring predetermined increments of liquid content material from a vessel into a measuring chamber provided with an air inlet to maintain atmospheric conditions within said chamber and dispensing a measured quantity of the content material from the measuring chamber through a dispensing conduit while the device is in dispensing position, an indicator from which the number of units dispensed may be read, means responsive to the filling of the measuring chamber for operating the indicator comprising a float responsive to the level of content material within the measuring chamber, an operative connection between the float and the indicator for effecting

the desired registration when the float has risen to the desired level, means resiliently engaging the indicator to prevent inadvertent adjustment thereof to make a different showing, and a stop pivotally mounted in the measuring chamber to militate against movement of the float to indicating position while the device is in other than pouring position.

10. In a measuring device of the type described operating on a siphon principle for repeatedly measuring predetermined increments of liquid content material from a vessel into a measuring chamber provided with an air inlet to maintain atmospheric conditions within said chamber and dispensing a measured quantity of content material from the measuring chamber through a dispensing conduit while the device is in dispensing position, a valve assembly including a ball member, a compartment within the chamber having passages which communicate the air inlet with the measuring chamber and in which the ball member is confined, a ball socket in a compartment wall adjacent one of said passages and wherein the ball normally seats when the device is in other than pouring position to close the adjacent passage and prevent flow of fluids therethrough, and means within the compartment limiting movement of the ball member out of the socket when the device is in dispensing position for opening the passage to establish communication between the measuring chamber and the inlet.

11. In a measuring device of the type described operating on a siphon principle for repeatedly measuring predetermined increments of liquid content material from a vessel into a measuring chamber provided with an air inlet to maintain atmospheric conditions within said chamber and dispensing a measured quantity of the content material from the measuring chamber through a dispensing conduit while the device is in dispensing position, an indicator from which the number of units dispensed may be read, means responsive to the filling of the measuring chamber with the predetermined increment of liquid for operating the indicator to record such filling, means resiliently engaging the indicator to prevent inadvertent adjustment thereof to make a different showing, and means including a spring pressed lever pivoted to a central portion of a housing assembly and having a spring dog at one end and a platform at the other, and an operative connection between the dog and the indicator to return same to zero position responsive to actuation of the platform from the under side of the device when free of the vessel with which it is adapted to be used.

12. In a measuring device of the type described operating on a siphon principle for repeatedly measuring predetermined increments of liquid content material from a vessel into a measuring chamber provided with an air inlet to maintain atmospheric conditions within said chamber and dispensing a measured quantity of the content material from the measuring chamber through a dispensing conduit while the device is in dispensing position, a valve operating in the air inlet to close the inlet and prevent escape of liquid content material while the device is in other than dispensing position and including a compartment within the measuring chamber having passages which communicate the air vent with the measuring chamber, a ball confined within the compartment and movable to a position which

closes one of the passages, when the device is in other than dispensing position and movable to a position away from the passage when the device is in dispensing position.

13. A measuring device as claimed in claim 12 in which the compartment is dimensioned to permit slight movement of the ball between its top and bottom wall and a socket is provided in the bottom wall in which the ball rests when the device is in other than dispensing position.
